BOAT HULL

Robert B. Stuart, R.D. 4, Penn Yan, N.Y. 14527

Continuation-in-part of design application Ser. No. 14,307,
Nov. 4, 1968. This application May 1, 1970, Ser.
No. 22,781

Term of patent 14 years

Int. Cl. D12—06

U.S. Cl. D71—1

FIG. 3

FIG. 4

FIG. 5

FIG. 6

FIG. 1 is a perspective view of the bottom and stern end of the boat hull taken from a point of view aft of and below the stern;

FIG. 2 is a stern elevation of the boat hull of FIG. 1;
FIG. 3 is a bottom view of the boat hull of FIG. 1;

FIG. 4 is a perspective view of the bottom and stern end of another species of the boat hull, taken from a point of view aft of and below the stern;

FIG. 5 is a stern elevation of the boat hull of FIG. 4;
FIG. 6 is a bottom view of the boat hull of FIG. 4;
FIG. 7 is a side elevation of the hull of FIG. 1; and
FIG. 8 is a side elevation of the hull of FIG. 4.

This application is a continuation-in-part of my earlier application, Ser. No. D.14,307, filed Nov. 4, 1968, and now abandoned.

The interior surface of the hull of each form is generally plain and in conformance with the illustrated exterior surface.

I claim:

The ornamental design for a boat hull, substantially as shown and described.
